UNITED STATES PATENT OFFICE.

DAVID PATTON BURDON, OF JACKSONVILLE, FLORIDA, ASSIGNOR OF ONE-HALF TO PAUL SATTELKAU, OF SAME PLACE.

VACUUM WATER-ELEVATOR.

SPECIFICATION forming part of Letters Patent No. 460,845, dated October 6, 1891.

Application filed June 13, 1891. Serial No. 396,173. (No model.)

To all whom it may concern:

Be it known that I, DAVID PATTON BURDON, a citizen of the United States, residing at Jacksonville, in the county of Duval and State 5 of Florida, have invented a new and useful Vacuum Water-Elevator, of which the following is a specification.

This invention relates to steam vacuum water-elevators; and it has for its object to 10 provide a device of this class which shall be simple in construction, durable, and effective in operation, and by means of which large quantities of water may be raised quickly and economically.

15 With these ends in view the invention consists in the improved construction, arrangement, and combination of parts, which will be hereinafter fully described, and particularly pointed out in the claims.

20 In the drawings hereto annexed, Figure 1 is a side elevation, partly in section, of a steam vacuum water-elevator constructed in accordance with my invention and showing the same at rest in its initial position. Fig. 2 is 25 similar view showing the machine in a position which it occupies in operation. Fig. 3 is a horizontal sectional view on the line 3 3 in Fig. 1, showing the foot-valve in plan view. Fig. 4 is a side elevation of the foot-valve. 30 Fig. 5 is a plan view showing the seat of the foot-valve. Fig. 6 is a horizontal sectional detail view taken on the line 6 6 in Fig. 1.

Like numerals of reference indicate like parts in all the figures.

35 1 designates a tubular upright having a tapering lower end 2, to which is attached a diaphragm or valve-seat 3, having a square or rectangular opening provided with cross-bars 5, forming separate inlet-openings 6, for 40 each of which an independent upwardly-opening valve 7 is provided. The several valves 7, which are hinged upon rods 8, mounted upon lugs 9 upon the valve-seat constitute the foot-valve or check-valve of my improved 45 water-elevator. The tubular upright 1 is provided at its upper end with upwardly-curved branch-pipes 10, supporting a tank 11, in which are arranged a pair of cylinders 12 and 12^a. The said cylinders are provided at their 50 lower ends with downwardly-tapering bases 13, which are polygonal in horizontal section,

so as to present a series of sides or faces 14, each of which forms a valve-seat, at the upper edge of which is hinged an upwardly and outwardly opening valve 15. The branch 55 pipes 10 open into the bases of the cylinders and are provided with seats 16 for the upwardly-opening valves 17, which are similar in construction to the foot-valve of the device.

The cylinders, which are closed at their upper ends, are provided near their upper ends with laterally and downwardly extending pipes 18, the inner ends of which support the perforated spray tubes or nozzles 19, extending 60 from their joint with said pipe downwardly within the cylinders, and the outer ends of said pipes are extended downwardly into the tank 11 at a point below the discharge-spout 20 of the latter. The spray- 65 tubes 19 are provided at their upper ends with concave diffusing disks or deflectors 21, which are arranged directly below the steam-inlet pipes 22, which are connected centrally to the upper ends of the cylinders. The inlet-pipes 22 are provided with valve-casings 70 75 23 for ordinary puppet-valves, the stems of which 24 extend upwardly and are connected pivotally with the levers 25, the outer ends of which are suitably pivoted to brackets 26 80 and the inner ends of which are provided with downwardly-extending pivoted rods or handles 27. The latter are provided with collars 28, which may be mounted adjustably 85 thereon by means of set-screws 29.

The bases or lower ends of the cylinders 12 12^a are provided with laterally-extending pipes 30, connected with chambers or casings 31, having upwardly-extending pipes 32, which are connected with the cylinders near 90 the upper ends of the latter. The upper ends of the pipes 32 are provided with packing-boxes 33, forming guides for the vertically-sliding rods 34, the lower ends of which are also guided in recesses 35 in the lower ends 95 of the chambers or casings 31. The vertically-sliding rods 34 are provided inside the chambers or casings 31 with cups, floats, or weights, as 36, for the purpose of operating the said rods, as will be hereinafter more 100 fully described. While either cups, floats, or weights will answer for the purpose indicated,

I have in the drawings hereto annexed illustrated cups only, inasmuch as this is deemed preferable for the purpose of illustrating the operation of the invention. The upper ends 5 of the rods 34 are connected with a lever or walking-beam 37, which is fulcrumed centrally between the said operating-rods at 38. The outer ends of the lever or walking-beam 37 are extended into the path of the collars 10 28 upon the rods or handles 27, depending from the operating-levers 25 of the valves.

It will be observed from the foregoing description that the equipment of the cylinders 12 and 12^a is identical in every respect.

15 The operation is as follows: One of the rods or handles 27 is operated by hand, so as to open the valve controlled thereby, thus admitting steam into the upper end of one of the cylinders 12 or 12^a, the tank 11 having 20 been previously partially filled with water, so as to seal the lower ends of the pipes 18. The steam on entering the cylinder is diffused by the deflecting-plate 21, and on condensing forms a partial vacuum, causing water to 25 be forced by the pressure of the atmosphere through the pipes 18 and spray-tube 19. When steam is again admitted, it becomes instantly condensed by the water distributed through the nozzle 19, thus forming a vacuum, 30 whereby the water is raised through the valve 7, tubular cylinder 1, and valve 17 into the cylinder 12 or 12^a, as the case may be. During this part of the operation the valves 15 of course remain closed by the pressure of the 35 water in the tank 11 and also by the vacuum formed in the cylinder. While the water rises in the cylinder in which the vacuum has been formed it rises correspondingly in the pipe 32 and chamber 31, connected with said cylinder, and this operation is repeated alternately with the valves of the two cylinders until both are filled with water, or nearly so. When steam is again admitted into one of the cylinders—for instance, the cylinder 12—the 40 water contained in said cylinder is forced out by the pressure of the steam through the valves 15 and into the tank 11, from which it escapes through the spout 20. When the water escapes from the cylinder 12, it simultaneously is lowered in the pipe 32 and chamber 31, connected with said cylinder, and the weight or cup 36 in the said chamber overbalances that contained in the chamber 31, connected with the cylinder 12^a, which, being 45 thus forced in an upward direction, serves, through the intermediate mechanism, to open the steam-inlet valve of the cylinder 12^a, the contents of which are now forced out through the valves 15 by the pressure of the entering 50 steam. In the meanwhile the steam in the cylinder 12 begins to condense, causing a partial vacuum, whereby water is drawn into the cylinder through the spray pipe or nozzle, which completes the condensation of the

55 steam, forming a complete vacuum, which causes the cylinder to be filled with water entering through the valves 17. At the same time the water escapes from the cylinder 12^a, causing the weight in the casing 36, connected with said cylinder, to be lowered, thus reversing the position of the steam-inlet valves. The operation will thus proceed rapidly and automatically, the two cylinders being alternately filled and discharged and the steam-inlet valves being alternately opened and 70 closed, as will be readily understood.

Having thus described my invention, what I claim is—

1. In a steam vacuum water-elevator, the combination of a tubular upright having a 80 foot-valve, a tank supported upon said upright, the cylinders mounted in said tank and connected with the tubular upright by branch pipes having valves opening into said cylinders, the upwardly and outwardly opening 85 valves at the lower ends of the latter, the pipes extending outwardly and downwardly from the said cylinders near the upper ends of the latter, the cylindrical spray tubes or nozzles connected to and suspended from the inner ends of said pipe and extending downwardly therefrom within the cylinders, the concave deflecting-plates at the upper ends 90 of said nozzles, and means for admitting steam into said cylinders alternately, controlled by the fall and rise of the water, substantially as and for the purpose herein set forth.

2. In a steam vacuum water-elevator of the class herein described, the combination of the 100 cylinders having the laterally and downwardly extending pipes, the perforated spray-tubes supported at the inner ends of said pipes and having concave deflecting-plates at their upper ends, the steam-inlet pipes at 105 the upper ends of said cylinders, valves arranged in said pipes and having upwardly-extending stems connected with operating-levers, the rods depending from the inner ends of said levers and having downwardly-extending rods provided with adjustable collars, the casings having upwardly-extending pipes connected with the cylinders near the upper and lower ends of the latter, the vertically-sliding rods having cups or their 115 described equivalents arranged in said casings, and the lever or walking-beam connected pivotally with said rods and having its ends extended into the path of the collars upon the rods of the valve-operating levers, substantially as and for the purpose set forth.

In testimony that I claim the foregoing as my own I have hereto affixed my signature in presence of two witnesses.

DAVID PATTON BURDON.
